CLAIM

The ornamental design for a screwdriver box, as shown and described.

DESCRIPTION

FIG. 1 is a front perspective view of a screwdriver box showing my new design, shown in an open position; FIG. 2 is a rear perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; FIG. 9 is a perspective view thereof, shown in a closed position; FIG. 10 is an enlarged detail view of area 10 in FIG. 1; FIG. 11 is an enlarged detail view of area 11 in FIG. 2; and, FIG. 12 is an enlarged detail view of area 12 in FIG. 2. The broken lines in the drawings illustrate the portions of the screwdriver box, which form no part of the claimed design. The dash-dot-dash broken lines encircling the enlarged views are for annotative purposes only and form no part of the claim thereof.

1 Claim, 12 Drawing Sheets
